Primary Examiner — Kimberly Barnes

(57) **CLAIM**

The ornamental design for a hand-held vacuum cleaner, as shown and described.

DESCRIPTION

FIG. 1 is a front perspective view of a hand-held vacuum cleaner, showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is another front perspective view showing the hand-held vacuum cleaner stored on a stand.

The broken lines in the drawings illustrate the portions of the hand-held vacuum cleaner, which form no part of the claimed design.

The broken lines in FIG. 8 depicting a stand and accessories represents environmental subject matter that forms no part thereof.

1 Claim, 8 Drawing Sheets
